UNITED STATES PATENT OFFICE.

ISAAC SCHNEER, OF NEW YORK, N. Y.

SHIRT.

SPECIFICATION forming part of Letters Patent No. 274,520, dated March 27, 1883.

Application filed November 28, 1882. (No model.)

To all whom it may concern:

Be it known that I, ISAAC SCHNEER, of New York, in the county and State of New York, have invented an Improvement in Shirts, of 5 which the following is a specification.

Figure 1 is a front view of my improved shirt; Fig. 2, an enlarged face view of part of the same, showing the additional face-strip partly folded down; Fig. 3, a cross-section on 10 the line *c c*, Fig. 2; and Fig. 4, a cross-section of a modification of the invention.

This invention relates to certain improvements in shirts, more particularly the kind known as "bicycle-shirts," which is a kind 15 having lacing in front, and has for its object, so far as the bosom part of the shirt is concerned, to allow the shirt to be readily opened and closed without interfering with the lacing, and to provide for one half of the laced 20 portion a face strip or piece which, except at the lower end, is disconnected from the shirt.

The invention also consists in applying a 25 pocket to the shirt directly below the bosom, and in utilizing the usual suspension-strap as a cover for that pocket.

In the accompanying drawings, the letter A represents the body of the shirt. In one 30 piece with this body are made the two parts, *a* and *b*, which meet, or nearly meet, in front over the bosom. The part *a*, near its edge, has series of eyelets or holes *d* in a vertical 35 row; but the part *b* has no such eyelets, but, on the contrary, is provided at quite a distance from its edge with series of buttons *e*. The part *a*, having the eyelets *d*, constitutes 40 one half of the bosom of the shirt. For the other half of the bosom I employ a separate strip, *B*, of fabric, which is fastened at its lower end by a short row of stitches, *f*, to the body of the shirt, and is otherwise not stitched 45 to the shirt. This separate strip *B* has, near one edge, a row of eyelets, *h*, and near the other edge a row of button-holes, *i*. The portion having the button-holes *i* is overlapped 50 by a narrow face-flap, *j*, which is attached to the strip *B*, so that the button-holes will not be exposed to view. To the inner side of the strip *B* is also fastened a flap, *l*, which laps 55 behind the part *a* of the bosom, as in Fig. 4, or said strip *l* may be attached to the inner side of the body *A*, behind the part *a*, as in Fig. 3. The inner edge of the strip *B* abuts 60 against the edge of the part *a*, and the lacing-

cord *C* is drawn through the eyelets or holes *d* and *h*, so as to unite the strip *B* with the 55 part *a*; but the shirt can be opened and closed without unfastening the cord *C* by simply unbuttoning the buttons *e* from the covered portion of the strip *B*, that has the button-holes *i*. By this means the effect is produced of a bosom 60 appearing to be laced and not otherwise secured, the buttons *e* being concealed when the shirt is closed, and yet the shirt can be opened and closed without interfering with the lacing, yet at the same time, when the strip *B* 65 is taken away, a complete shirt will remain.

Below the bosom part the shirt is provided with the suspension-piece *D*, having a button-hole which may be utilized to connect the shirt with the drawers or pantaloons, and below 70 this suspension-piece *D* is formed on the shirt a pocket, *E*, which has, at its upper part, a button, *m*, to which the flap *D* can be buttoned, as shown. This pocket *E* is in convenient position for holding a watch or other valuable article, and will not interfere with the freedom of movement of the wearer. For 75 gymnastic exercises, where a waistcoat is not usually worn, the shirt having this pocket will be found very convenient, much more so than one 80 having a pocket over the breast, which, when filled, will interfere with respiration.

I claim—

1. In a shirt, the combination of the body A, having bosom part *a*, with row of holes *d* 85 therein, and part *b*, with buttons *e*, the combination therewith of the face-strip *B*, which is fastened to the shirt only at the lower end, and which has a row of holes, *h*, button-holes, *i*, and covering-flap *j*, substantially as described. 90

2. The combination of the shirt A, having bosom part *a*, and part *b*, with the face-strip *B*, having face-flap *j*, and with the backing-flap *l*, buttons *e*, and lace-cord *C*, substantially 95 as described.

3. In a shirt, the combination thereof with the pocket *E*, placed entirely below the bosom, and with the flap *D*, that serves to cover said pocket and to connect the shirt with the lower garment, substantially as described. 100

This specification of my invention signed this 27th day of November, 1882.

ISAAC SCHNEER.
